FLOATING BAR

Rai B. Kelso, P.O. Box 659, Galveston, Tex. 77550, and
Larry F. Herndon, Jr., 3601 Oak Grove, Dallas, Tex.
75204

Filed June 10, 1968, Ser. No. 12,288

Term of patent 14 years

Int. Cl. D7—99

U.S. Cl. D44—10

Fig. 1

Fig. 2

FIGURE 1 is a perspective view from above of a floating bar showing our new design;

FIGURE 2 is a perspective view from below;

FIGURE 3 is a top plan view; and

FIGURE 4 is a cross-sectional view taken along the section line 4—4 of FIGURE 3.

We claim:

The ornamental design for a floating bar, substantially as shown.
